UNITED STATES PATENT OFFICE.

ALMA C. MILLER, OF MCKEESPORT, PENNSYLVANIA.

WINDOW-CURTAIN BRACKET.

SPECIFICATION forming part of Letters Patent No. 708,381, dated September 2, 1902.

Application filed June 5, 1902. Serial No. 110,309. (No model.)

To all whom it may concern:

Be it known that I, ALMA C. MILLER, a citizen of the United States of America, residing at McKeesport, in the county of Allegheny and State of Pennsylvania, have invented certain new and useful Improvements in Window-Curtain Brackets, of which the following is a specification, reference being had therein to the accompanying drawings.

10 This invention relates to certain new and useful improvements in window-curtain brackets, and has for its object a device of this character which shall embrace novel means whereby a curtain-pole supporting the curtain may be readily adjusted in a vertical direction.

15 A still further object of the invention is to enable the two ends of the curtain-pole to be adjusted in the desired direction simultaneously.

The invention has for its further object a device of this character which shall be of simple and economical construction as well as efficient in operation and cheap to manufacture.

With the above and other objects in view the invention consists in the novel construction, combination, and arrangement of parts, to be hereinafter more fully described, and 30 specifically pointed out in the claim.

In describing the invention in detail reference is had to the accompanying drawings, forming a part of this specification, and wherein like numerals of reference indicate like parts throughout the several views, in which—

Figure 1 is a front elevation of the device, showing the same attached to a window-frame. Fig. 2 is a side elevation thereof.

40 The window-frame (designated by the numeral 1) at its upper end receives the base-plates 2 at each side thereof, which base-plates are preferably of a rectangular form, as shown. Extending outwardly from the 45 base-plate, at right angles thereto and near the upper end thereof, is an arm 3, bifurcated at its outer end, as at 4, and receiving therein the pulley 5, grooved throughout its periphery. This pulley is adapted to 50 freely revolve upon the pin 6, which passes therethrough and is secured in the bifurcated end of the arm 3. A supporting mem-

ber 7 is secured in proximity to the lower end of the base-plate 2 and to the arm 3 to the rear of the pulley, so that this supporting member will not interfere with the movement of the pulley. The curtain-pole 8 carries a series of hooks 9 for supporting the curtain 10 and upon its upper side carries eyes 11, through which are passed the cords 12, the latter being secured to the eyes. These cords pass up over the pulleys and from thence pass downwardly, being engaged by the eyes 13, carried by the base-plate 2. The cord is secured to this eye 13 and from 65 thence passes downwardly through the eye 14, carried by the side of the window-frame, thence through corner eyes 15, from whence the cord is passed in alinement with the lower end of the window-frame and down 70 through the locking hook or member 16. Both ends of the cords on each side of the window-frame are joined or knotted, as at 17, and have their free ends 18 extending below the locking member 16 in order that the said ends 75 may be readily grasped by the fingers, and by pulling downwardly upon the same the curtain-pole will be lifted at its ends and in an even manner. It will be noted that the eyes 14 will also be used for the purpose of passing 80 the cords 18^a therethrough, the latter serving to drape the curtain near its ends.

In operation it will be noted that the curtain-pole may be readily locked in any desired position by merely knotting the free 85 ends 18 of the cords at such position that when the knot is engaged by the locking member 16 the pole will occupy the desired position. This can be readily determined by pulling down upon the free ends 18 of the cords 90 and tying the knot therein, the knot being engaged by the locking member and preventing the pole from having any further downward movement.

While I have shown in this illustration the 95 most practical embodiment of my invention, still it is obvious that slight changes may be made in the details of construction and combination of parts without departing from the general spirit of my invention.

Having fully described my invention, what I claim as new, and desire to secure by Letters Patent, is—

In a device of the type set forth, the combi-

- nation with a window-frame, of a base-plate carrying an arm bifurcated at its outer end with a pulley mounted in the bifurcated portion, an eyelet carried by the base-plate, a curtain-pole having hooks on its lower side to receive the curtain, hooks on the upper side of the pole with cords engaging said hooks, passing over said pulley and through the eyelets carried by the base-plate, eyelets carried
5 by the window-frame at the corners thereof, and an eyelet secured intermediate the width of said window-frame, said cord adapted to

pass through said eyelets and have their free ends knotted and passed through said eyelet located intermediate of the window-frame, 15 with the knotted portion on the under side of the eyelet, substantially as described.

In testimony whereof I affix my signature in the presence of two witnesses.

ALMA C. MILLER.
